UNITED STATES PATENT OFFICE.

WILLIAM H. MAGEE, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS GOBLET OR SIMILAR ARTICLE.

Application filed August 7, 1925. Serial No. 14,332. Term of patent 14 years.

To all whom it may concern:

Be it known that I, WILLIAM H. MAGEE, a citizen of the United States of America, and resident of Moundsville, county of Marshall, and State of West Virginia, have invented a new, original, and ornamental Design for a Glass Goblet or Similar Article, of which the following is a specification,

reference being had to the accompanying drawings, in which—

The figure is a side elevation of a glass goblet, showing my new design.

I claim:

The ornamental design for a glass goblet or similar article, as shown.

WILLIAM H. MAGEE.
